B. H. SKELLY

MEANS FOR LUBRICATING STEERING KNUCKLES OF VEHICLES

Filed April 25, 1923

Inventor

Bernard H. Skelly

ATTORNEY

UNITED STATES PATENT OFFICE.

BERNARD H. SKELLY, OF BRIDGEPORT, CONNECTICUT, ASSIGNOR TO BOWEN PRODUCTS CORPORATION, OF AUBURN, NEW YORK, A CORPORATION OF NEW YORK.

MEANS FOR LUBRICATING STEERING KNUCKLES OF VEHICLES.

Application filed April 25, 1923. Serial No. 634,436.

To all whom it may concern:

Be it known that I, BERNARD H. SKELLY, a citizen of the United States, residing at the city of Bridgeport, in the county of Fairfield and State of Connecticut, have invented certain new and useful Improvements in Means for Lubricating Steering Knuckles of Vehicles; and I do declare the following to be a full, clear, and exact description of the invention, such as will enable others skilled in the art to which it appertains to make and use the same.

This invention relates to the lubrication of the steering knuckles of vehicles, particularly automobiles, and has for its objects, first to lubricate the joints of the knuckles of the part that carries the steering wheels as well as the joints where the connecting bar engages the tie rod, from a single supply of lubricant, and second, to lubricate all the movable parts, connected with the tie rod and the axle and comprising the steering system complete at both ends of the axle, from one source of lubricant supply of the force feed type.

Other objects and advantages of the invention relate to the details of the structure, all as will more fully appear from the following description taken in connection with the accompanying drawings, in which:—

Figure 1 is a broken view looking at the axle and tie-rod from above and at an angle and showing particularly how my invention is installed.

Figure 2 is a broken front elevation of the axle and tie-rod equipped as shown in Figure 7.

Figure 3 is a section at line 9—9 of Figure 2.

Figure 4 is a section at line 10—10 of Figure 2.

Similar numerals of reference denote like parts in the several figures of the drawing.

In the drawing 41 is a distributing union which is secured to the axle 1, in any suitable manner. As shown at Figure 4, this union has a portion 42 that conformably fits against the side of the axle and a bolt member 43 that extends through the axle with a nut 44 driven on the end of the bolt. A conduit 45, which is the sole lubricant supply and leads from a force feed pump, is connected with a nipple 46, the latter being a

part of a swivel connection with the union such as is shown and described in my patent 55 aforesaid. A similar nipple 47 is a part of another swivel connection with the union, these two connections being preferably disposed at right angles to each other and communicating with passages 48 and 49 that 60 intersect. The passage 48 is in line with the supply nipple 46 and extends beyond the passage 49 and leads into a passage 50 which extends in opposite directions through the union and is connected at the respective ends 65 to the conduits 51 and 52 which lead to the two steering knuckles at opposite ends of the axle.

From the passage 49 the lubricant passes through the flexible conduit 53 into the nipple 54, which latter is a part of a swivel connection, as aforesaid, with a distributing union 55 that is fixed on the tie rod 15 in any suitable way. This union 55 has a passage 56 leading from the swivel connection 70 54 into a cross-passage 57 that extends in opposite directions through the union and is connected at the respective ends to the copper tube conduits 58 and 59 which lead to the two tie rod bolt journals at opposite 75 ends of said rod.

Owing to the various movements of the tie rod, and the great jarring and vibration of the axle, the flexible conduit 53 and the swivel connections mentioned, are necessary, 85 since otherwise, the conduits are apt to break and the nipple connections would probably be so wrenched and strained that they would either break or leak.

While I have not described any particular means for supplying lubricant either through the conduit A or the conduit 45, the same may be supplied under force feed by the means shown and described in my Letters Patent of the United States No. 95 1,326,142, issued December 23, 1919, wherein I have disclosed a lubricating system for an automobile chassis.

What is claimed is:—

1. The combination with the steering 100 knuckle system of an automobile, in which the knuckle portions associated with the axle and tie-rod are provided with lubricant passages, of distributing unions secured to said axle and rod, a single force feed lubricant conduit leading into one of said unions,

a flexible conduit connection between said unions, and auxiliary conduits leading from said unions to said passages.

2. In the steering system of an automobile, the combination with the tie-rod and axle knuckles, of flexibly interconnected distribution unions secured respectively to said rod and axle, a single conduit for a force

fed lubricant leading into one of said unions, and conduits extending from each union in opposite directions in each instance and respectively leading into said knuckles. In testimony whereof I affix my signature hereto.

BERNARD H. SKELLY.
